Patented Jan. 29, 1918.

UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

SELECTOR-SWITCH-MOVEMENT-CONTROLLING CIRCUIT.

1,254,710.

Specification of Letters Patent. Patented Jan. 29, 1918.

Application filed January 29, 1916. Serial No. 751,311.

To all whom it may concern:

Be it known that I, ALBEN E. LUNDELL, a citizen of the United States, residing at New York city, in the county of Bronx and State of New York, have invented certain new and useful Improvements in Selector-Switch-Movement-Controlling Circuits, of which the following is a full, clear, concise, and exact description.

10 This invention relates to a system for controlling the movement of selector switches for use in automatic telephony.

Its object is to improve in general the construction and arrangement of the parts of the switch mechanism used in conjunction with the switch movement controlling circuit, whereby the interconnection of a large number of lines may be effected with rapidity and precision.

20 One feature of the invention resides in directly associating a pair of contact springs with a pawl, the latter engaging a series of slots in a rack which serves to position the movable parts of the switch. The contact springs are operated by the movement of the pawl to send impulses which control the operating magnets of the switch. Contacts are provided for group and individual line selection.

30 Another feature of the invention is directed to the utilization of the momentum of the rack or moving brush carriage following the long step group selecting interval to operate the retaining pawl of the brush carriage, which in turn serves to prepare the circuit for individual contact selection in the selected group.

The invention is illustrated in the accompanying drawings in which Figure 1 shows 40 the circuit of a complete connection in which the selector switch movement controlling circuit is utilized. Fig. 2 illustrates the operating pawls of the connector switch in their normal relation to the rack of the switch and Fig. 3 illustrates the pawls in their operated relation.

In the embodiment of my invention as shown in the drawing, the invention has been adapted to a semi-automatic system and the 50 connector switch is controlled by any type of sender which is set and operated by the switchboard operator. The invention is not restricted to use with the particular system

55 In the present embodiment of the invention the sender, disclosed in the patent to Lundell, No. 1,168,319, January 18, 1916, has been used, but it will be evident that the invention may be readily adapted to any one of 60 the well-known types of senders, whether of the reverse or direct impulse sending type.

The invention may best be explained by a detailed description of the operation of the circuit shown in Fig. 1. When the calling subscriber removes his receiver from the hook he will operate the line relay 6 in the well-known manner which in turn will illuminate the line signal. The operator upon observing the illuminated line signal will insert an idle answering plug into the jack associated with the displayed signal. This will complete a circuit from the ground at the cut-off relay 7 by way of the sleeve strands of the jack and plug to the sleeve relay 8 of the cord circuit and thence to battery. The operation of the cut-off relay 7 will disassociate the line signaling apparatus from the calling subscriber's line and extinguish the calling line lamp. The sleeve relay 8 in operating will complete a circuit from ground on its armature by way of its make contact and the upper left-hand contact of sequence switch spring 11 to the sequence switch power magnet 10 and thence to battery. This will cause the operation of the sequence switch, which will move into its second position. In the second position of the sequence switch a circuit is closed from ground at the stepping relay 9 of the 90

sender through the break contact and armature of the last counting relay 10 of the sender by way of sequence switch spring 12 of the sender and the lower right-hand contact of sequence switch spring 13 and thence through relay 14 to battery. The operation of relay 14 will close a circuit from the ground on its right-hand armature by way of its make contact, lower right-hand contact of sequence switch spring 11 and the power magnet of the sequence switch to battery. The sequence switch will, therefore, move into its third position.

In the third position of the sequence switch a circuit is closed from battery 105 through the clutch magnet 15, the upper

right-hand contact of sequence switch spring 16 and the make contact and right-hand armature of relay 14 to ground. The operation of the clutch magnet 15 will force the rack 18 against the high-speed constantly driven power shaft 19 and thus cause the elevation of the brush carriage. The brush carriage in its upward movement will cause the movable contacts 20 to sweep over the stationary contacts of the contact bank 21. In the upward movement of the brush carriage the pawl 24 engages the series of elongated slots in the rack 18. As will be observed from Fig. 2, when the pawl is resting on the surface of the rack, the contact springs 25 and 26 controlled thereby, are out of contact. However, when the pawl 24 drops into one of the slots, the horizontally extending arm of the pawl is moved in an upward direction and the spring 25 is moved toward the spring 26 and the contact between these two springs is closed as shown in Fig. 3. When this contact is closed a circuit is completed from ground connected to spring 26 by way of spring 25, the upper left-hand contact of sequence switch spring 13, the left-hand armature of relay 14 and through the coil of this relay to battery. This circuit is completed at the left-hand armature of relay 14, since this relay was permanently locked at this contact, directly after the sequence switch moved into its second position, over a circuit which may be traced from battery through the coil of the relay, the make contact and left-hand armature of the relay, the contact of sequence switch spring 12, the armature and break contact of relay 10 of the sender and relay 9 of the sender to ground.

It will be observed that the locking circuit of relay 14 just traced has a parallel path to ground from its left-hand armature whenever the circuit closed by the contacts 25 and 26 is operated by the pawl 24. This parallel circuit to ground through the springs 25 and 26 will shunt out relay 9 of the sender and deenergize the same, and this relay will be deenergized each time the pawl 24 engages one of the series of elongated slots in the rack 18. This number of deenergizations of relay 9 will be equal in number to the first digit of the number set up by the operator on the sender. After the first set of impulses have been sent the last counting relay #10 of the sender is operated and the fundamental sending circuit is opened at the armature of this relay. The opening of the circuit at this contact will open one of the parallel paths of the relay 14. The other path through the contacts 25 and 26 will likewise be opened because the momentum acquired by the brush carriage in the group selection results in an overthrow sufficient to carry the rack on so that the pawl 24 will be moved out of the last engaged elongated slot for group selection and the pawl 30 utilized for individual contact selection in the group selected will engage the first short slot of the selected group.

An inspection of the rack of the brush carriage will indicate that it is equipped with a long slot, which traverses most of its face, for each group of stationary contacts and that between each two of these long slots there is a series of nine short slots which with one of the long slots, are equal in number to the number of contacts in a group. This arrangement of slots in the rack results in a movement of the pawl 24 for each group of contacts traversed by the contact brushes 20 and a movement of the pawl 30 for each group of contacts and for each individual contact in each group traversed by said brushes.

Due to the opening of the circuit of relay 14 at the contact of relay 10 and at the springs 25 and 26 the relay will be deenergized and a circuit is closed from the ground at its right-hand armature by way of its break contact, lower left-hand contact of sequence switch spring 11 and the power magnet of the sequence switch to battery. This will move the sequence switch into its fourth position. In the fourth position of the sequence switch a circuit is closed for relay 14 which may be traced from battery through the relay, the lower right-hand contact of sequence switch spring 13, sequence switch spring 12 of the sender, the armature of relay 10 and the coil of relay 9 to ground. This circuit is completed through the sender mechanism due to the fact that the sender has been reset for the selection of individual contacts after the last counting relay 10 was deenergized at the end of the period during which impulses for group selection was sent.

The operation of relay 14 closes a circuit from ground at the right-hand armature of this relay through its make contact, the lower right-hand contact of sequence switch spring 11 and the power magnet 10 of the sequence switch to battery. This will move the sequence switch into position 5. As shown in Figs. 2 and 3 when the pawl 30 is resting on the surface of the rack, that is, in its normal position, the contact springs 33 and 34 are closed. It will be remembered, however, that due to the momentum acquired by the brush carriage in group selection the rack 18 was carried beyond the last selected group slot and the pawl 30 was inserted into the first short slot of the selected group thereby preparing the set, utilized in individual contact selection. When the relay 14 operated during the time the sequence switch was in position 4 it closed for itself a locking circuit, which may be traced from battery through coil of the relay, its make contact and the right-hand armature of relay 14.

tact and left-hand armature and sequence switch spring 12 of the sender, armature and contact of relay 10 and the coil of relay 9 to ground. This circuit has a parallel path 5 to ground from the left-hand armature of the relay by way of the upper right-hand contact of sequence switch spring 13 and the switch springs 34 and 33 to ground. However, since the pawl 30 is resting in the first 10 slot of the group selected the contact between the springs 33 and 34 is opened as the sequence switch is moved into its fifth position.

In the fifth position of the sequence switch 15 a circuit is closed for the clutch magnet 36, which can be traced from battery through the magnet, the lower contact of sequence switch spring 16 and the make contact and armature of relay 14 to ground. The clutch magnet 36 in operating will press the rack 18 against the constantly rotating power shaft 38. The brush carriage will therefore begin to move up in the group selected to 20 select the desired set of contacts of the selected group. As the brush contacts 20 move past each set of stationary contacts of the bank 21, the pawl 30 will ride into one of the slots in the rack of the selected group. As the pawl 30 leaves each slot and rides 25 upon the surface of the rack the contact between springs 33 and 34 is closed and the circuit through the stepping relay 9 of the sender is shunted in a manner similar to that described for group selection.

When the desired number of impulses 30 have been sent to select the desired set of contacts of the selected group, which is controlled by the number set up by the answering operator, on the sender mechanism, the last counting relay 10 of the sender is operated and the fundamental circuit is opened at the armature of the last counting relay 10. At the same time, since the pawl 30 engages one of the slots of the selected 35 group the contact between the springs 33 and 34 is also opened. The circuit of relay 14 is, therefore, broken and the relay is deenergized and in its deenergized position a circuit is closed from the ground on its right-hand armature by way of its break contact, the lower left-hand contact of sequence switch spring 11 and the power magnet 10 of the sequence switch to battery. The sequence switch will, therefore, move 40 into its sixteenth position. In this position of the sequence switch the talking strands of the calling cord are closed at sequence switch springs 40 and 41 and since the movable contacts 20 have been moved to connect with the desired stationary contacts of the contact bank, a circuit is closed to the called subscriber's line. This circuit may be traced from battery through one winding of the repeating coil, sequence switch spring 40, 45 the tip contact of the brush and contact bank

through the calling subscriber's loop and back over the ring side of the line, the ring contact of the bank and brush and through the sequence switch spring 41 and the other winding of the repeating coil to battery. A 50 circuit is also completed from battery by way of sequence switch spring 42 through the cut-off relay of the calling line to ground. This disassociates the calling subscriber's 55 signaling apparatus from his line circuit.

When the subscribers have completed their 60 conversation the operator will remove the answering plug from its associated jack and thereby deenergize the sleeve relay 8. This will close a circuit from the ground on the 65 armature of said relay by way of the upper right-hand contact of sequence switch spring 11 and the power magnet of the sequence switch to battery. The sequence switch will consequently move into its eighteenth position. In the eighteenth position of the sequence switch a circuit is closed from ground through the release clutch magnet 48 and the sequence switch spring 49 to ground. Consequently the release clutch magnet will press 70 the rack 18 against the constantly driven power shaft 50, and since this shaft revolves in a direction opposite to that of the shafts 19 and 38 the brush carriage will be returned to normal. The release clutch magnet 48 in 75 operating likewise removes the pawls 30 and 24 from their engaged slots by means of the arm 51 so that these pawls will not interfere with the return movement of the rack. When the switch has returned to its normal 80 position the normal springs 52 and 53 of the switch will be closed, which will complete a circuit from ground by way of these springs through the upper right-hand contact of sequence switch spring 54 and the power magnet 10 of the sequence switch to battery. This will move the sequence switch back to 85 its first position and thus open the circuit of the release clutch magnet. The apparatus has now all been returned to its normal position and is in condition for another call.

Obviously this invention is not limited to the specific embodiment herein shown and described, but is capable of many variations and applications without departing from its 90 spirit and scope.

What is claimed is:—

1. In an automatic switch mechanism, having stationary and movable contacts, a circuit controlling the movement of said movable contacts in the selection of stationary contacts, and means independent of said movable contacts but operated in the movement of said movable contacts to lock the same in position and to control said circuit.

2. An automatic switching mechanism, having a primary and secondary movement, stationary and movable contacts, a circuit controlling the primary movement of said mechanism, means operated during the 100

- primary movement to control said circuit, a circuit controlling the secondary movement of said mechanism, and means operated during the secondary movement to lock said 5 movable contacts in position and control said second circuit.
3. In an automatic switching mechanism, having stationary and movable contacts, a circuit controlling the movement of said 10 movable contacts in the selection of stationary contacts, and a pawl operated in the movement of said movable contacts to lock the same in position and control said circuit.
4. In an automatic switching mechanism, 15 having a primary and secondary movement, stationary and movable contacts, a circuit controlling the primary movement of said mechanism, a pawl operated during the primary movement to control said circuit, a circuit controlling the secondary movement of said mechanism, and a pawl operated during the secondary movement to lock said movable contacts in position and control said second circuit.
5. In an automatic switch, a plurality of stationary contacts, an element equipped with movable contacts coöperating therewith, means to advance said movable contacts to select a desired set of stationary contacts, 30 a circuit adapted to control said movement, and a single means operated by said moving element to retain it in its displaced position and to control said circuit.
6. An automatic switch, having a plurality of stationary contacts, a movable rack equipped with contacts to coöperate with said stationary contacts, a circuit controlling the movement of said rack, and means operated by said rack to retain it in its displaced 40 position and to control said circuit.
7. An automatic switch, having a plurality of stationary contacts, a movable rack equipped with contacts to coöperate with said stationary contacts, a pawl which engages a series of slots in said rack to retain it in its actuated position, and a circuit governing the movement of said rack, such circuit being controlled by the operation of said pawl.
8. In an automatic switch, a plurality of stationary contacts divided into groups, a movable rack provided with slots and equipped with contacts which coöperate with said movable contacts, a circuit controlling 50 the movement of said rack to select a desired group of terminals, a pawl engaging a series of said slots which control said circuit, a second circuit controlling the movement of said rack to select the desired contacts of the selected group, and a second pawl engaging a second series of said slots to maintain the contacts in the selected position and to control said second circuit.
9. In an automatic switch controlling system, the combination with stationary terminals, of a rack equipped with terminals to coöperate with said stationary terminals, a constantly rotating power shaft, a magnetic clutch controlling the connection of said rack with said power shaft, a circuit controlling 70 said magnet and a pawl engaging a series of slots in said rack adapted to retain the rack in its displaced position and to control said circuit.
10. In an automatic switch controlling system, stationary terminals divided into groups, a rack equipped with terminals to coöperate with said stationary terminals, a constantly rotating power shaft, a magnetic clutch controlling the connection of said 75 rack with said power shaft for group selection, a circuit controlling said magnet to select a desired group, a pawl engaging a series of slots in said rack adapted to control said circuit, a constantly rotating power 80 shaft for individual contact selection, a magnetic clutch controlling the connection of said rack with said power shaft for individual contact selection, a circuit controlling the said second magnet and a pawl engaging a 85 second series of slots in said rack adapted to retain the rack in its displaced position and to control said circuit.
11. In a controlling system for a switching mechanism, having primary and secondary movement, stationary contacts, movable contacts coöperating therewith, means operable in the primary movement of said mechanism to effect a primary selection, a circuit controlling the secondary movement of said 90 switching mechanism, and means operated by the overthrow of the movable contacts resulting from the primary selection to position said contacts and prepare the circuit controlling the secondary movement.
12. In a controlling system for switching mechanism, having primary and secondary movement, stationary contact springs divided into groups, movable contact springs coöperating with said stationary contacts, means operated in the primary movement of said switch to select a desired group of stationary contacts, a circuit controlling the secondary movement of said switch to select a particular set of contacts in the group selected, and means operated by the overthrow of said movable contacts resulting from the group selection to position said movable contacts and prepare the circuit controlling the individual contact selection.
13. In an automatic switch controlling system, stationary terminals divided into groups, a switch carriage carrying terminals to coöperate with said stationary terminals, a constantly rotating power shaft for group selection, a magnetic clutch controlling the connection of said switch carriage with said power shaft for group selection, means operable to control said magnetic clutch to select the desired group, a constantly rotating 125
14. In an automatic switch controlling system, stationary terminals divided into groups, a switch carriage carrying terminals to coöperate with said stationary terminals, a constantly rotating power shaft for group selection, a magnetic clutch controlling the connection of said switch carriage with said power shaft for group selection, means operable to control said magnetic clutch to select the desired group, a constantly rotating 130

power shaft for individual contact selection, a magnetic clutch controlling the connection of said switch carriage with said power shaft for individual contact selection, a circuit 5 controlling the said second magnet, and means operated by the overthrow of said brush carriage following the group selection

to position the brush carriage and prepare the controlling circuit of said magnetic clutch for individual contact selection.

10

In witness whereof, I hereunto subscribe my name this 24th day of January A. D., 1916.

ALBEN E. LUNDELL.
